UNITED STATES PATENT OFFICE.

HENRY L. PITMAN, OF WESTFIELD, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed March 17, 1923, Serial No. 625,699. Renewed July 18, 1925.

To all whom it may concern:

Be it known that I, HENRY L. PITMAN, a citizen of the United States, residing in Westfield, in the county of Union and State 5 of New Jersey, have invented certain new and useful Improvements in Typewriting Machines, of which the following is a specification.

This invention relates to means for automatically tabulating a paper-carriage or other letter-feeding carriage of a typewriter at one or more predetermined points in a line of writing, and is in the nature of an improvement on my co-pending application, 15 Serial No. 621,520, filed February 27, 1923.

In said co-pending application the letter-feeding movement of the paper-carriage is controlled by a rack pivotally mounted on the carriage and normally meshing with a 20 pinion permitted to advance one step at a time at each operation of the escapement mechanism. The teeth of the rack are at letter-space intervals, and the pinion is of such size that two of its teeth are always 25 in position to mesh with the rack. For automatically tabulating the carriage teeth are omitted to form gaps separated by a single isolated tooth, which stops the carriage in a column in which typing is to be effected by 30 but a single operation of a type-bar before the next automatic tabulating movement occurs. Operation of a type-bar to print in this column causes the pinion to be advanced one step, and unless provision is 35 made for lifting the rack at this instant the single isolated tooth remains in engagement with the same tooth on the rack. To effect such lifting of the rack at the proper time, use is made of a member or yoke so 40 positioned on the rack-bar as to engage at that instant the usual roll by which the rack is lifted in connection with manual tabulation. It is desirable to lift the rack just 45 enough to clear the pinion, and it would be necessary to exercise great care in making the roll-engaging part of the yoke of the right thickness.

According to the present invention, provision is made of improved automatic rack-lifting means adjustable to fix with suitable 50 precision the extent of the lifting of the rack.

In the preferred form of the invention, the temporary lifting of the rack is effected

by engagement of the usual rack-lifting roll 55 by a member threaded through the rack at one side of the row of teeth and extending downwardly so that, when the carriage reaches the predetermined letter-space position, the lifting member will ride over the roll and temporarily disengage the rack from the pinion. By using a fine thread for the screw, the extent of the downward projection of the lifting member may be adjusted as precisely as required. The lifting member 60 may be secured in adjusted position by suitable means, such as a locking nut.

The threaded lifting member is provided at its lower end with opposite cam-surfaces 70 so as to be effective in both directions of movement of the carriage. This arrangement limits the adjustment to that obtained by turning the threaded member to the nearest half rotation.

It will be seen that, inasmuch as the adjustable lifting member does not extend across the row of teeth, it will not affect the engagement of the pinion with the rack at any point except the one desired.

Other features and advantages will hereinafter appear.

In the accompanying drawings,

Figure 1 is a diagrammatic side elevation, partly in section, showing the invention applied to so much of an Underwood 85 standard typewriting machine as is necessary for the purpose of illustration.

Figure 2 is a detail view, showing the relative positions of the rack and pinion at the end of the first automatic tabulating 90 movement.

Figure 3 is a view similar to Figure 2, but with the rack lifted as the single isolated tooth thereon is released from the pinion-tooth engaged thereby in Figure 2.

Figure 4 is a view similar to Figures 2 and 3, showing the relative positions of the rack and pinion at the end of the second automatic tabulating movement.

Figure 5 is a detail view, partly in section, 100 of the adjustable means for lifting the rack.

Figure 6 is a view of the screw-member by which the extent of lifting of the rack is determined.

Upon an actuation of type-keys (not 105 shown), the usual bell-cranks 11 will be actuated to swing type-bars 12 upwardly and rearwardly, to cause types 13 thereon to

strike against a platen 14 in a carriage 15, supported at the rear on a rail 16, and urged in a letter-feeding direction by means of a spring-drum 17.

5 Movement of the carriage 15 in letter-feeding direction is controlled by means of a rack 18, pivotally mounted on the carriage by means of arms 19, and having on its lower face teeth 20, at letter-space distances, 10 meshing with teeth 21 on a pinion 22. The pinion 22 has a one-way connection with an escapement wheel 23 by means of a pawl 24, pivoted on the escapement wheel at 25, and urged into engagement with the teeth 21 15 by means of a spring 26, thus permitting substantially free movement of the pinion 22 by the rack when the carriage is returned, but preventing movement of the pinion 22 relatively to the escapement wheel 23 when 20 the carriage is fed in a letter-feeding direction.

Normally the carriage is held against letter-feeding movement by means of a loose dog 27 in engagement with a tooth of the 25 escapement wheel. The loose dog 27 is pivotally mounted on a dog-rocker 28, so to swing transversely of the machine, and normally is held against a stop 29 on the dog-rocker against the action of a spring 30. As an actuated type-bar 12 nears the 30 end of its typing movement, a heel 31 thereon engages a universal bar 32, forming part of a universal frame 33, and swings the dog-rocker 28, so as to withdraw 35 the loose dog from engagement with the escapement wheel, and to move a fixed dog 34 on the dog-rocker 28 into engagement with the escapement-wheel tooth just released by the loose dog. The loose dog 27 40 is then drawn to the left by the spring 30, and, upon release of the dog-rocker 28 and return thereof to normal position, the loose dog 27 will engage the next tooth to the left (Figure 2), and the spring-drum 17 45 will advance the escapement wheel 23 against the action of the spring 30 until the loose dog 27 again engages the stop 29.

Upon actuation of a tabulator-key (not shown), a link 35 is drawn downwardly, 50 thereby rocking a frame 36 forwardly about its pivot 37, to bring a column-stop 38 thereon into the path of a finger 39, mounted on the rear of the carriage. The frame 36 comprises a lower bar 40, ends 41 and a top bar 42, having on its inclined face a scale 43 to assist in positioning stops 38 in the desired letter-space positions. Each stop 38 is pivotally and slidably mounted on a rod 44, supported in the ends 41 of the 55 frame 36, and is held in position by the projection of its upper end into one of the series of notches 45 at letter-space positions in the lower edge of the bar 42. When it is desired to change the position of a stop 60 65 38, it is swung downwardly and rear-

wardly by means of a handle 46 to withdraw its upper edge from the corresponding notch 45, and then moved along the rod 44 to the desired position. Each stop 38 is provided with a pointer 47 to co-operate with the scale 43. Upon completion of such adjustment along the rod 44, the stop 38 is swung forwardly to carry its upper end into the corresponding notch 45.

To enable the tabulation of the carriage 15 when the stop-frame 36 is swung forwardly, provision is made of an arm 48 extending forwardly from the bar 40, so that, upon forward rocking of the frame 36, the arm 48 will engage the rear end of a lever 49 and swing it about its pivot 50, to cause a roll 51 on the forward end of the lever to lift the rack 18 out of engagement with the pinion 22, thus permitting the carriage to advance until the finger 39 engages one of the stops 38. The roll 51 engages a track portion 18^a of the rack 18, immediately to the front of the teeth 20, and normally limits the downward movement of the rack. In order to position the roll at the proper elevation, the lever 49 is provided with a set-screw 52 to engage a portion of a bracket 53 on which the lever 49 is pivoted.

For certain kinds of work, it is found desirable to tabulate the carriage automatically, and, for this purpose, certain teeth 20 of the rack 18 are omitted. As herein disclosed, provision is made of two gaps in 100 the rack-teeth separated by a single tooth 20^a, the arrangement being the same as in 105 said co-pending application.

As shown in Figure 2, the single tooth 20^a is in engagement with the tooth 21^a of the 105 pinion 22. A single operation of the escapement mechanism will advance the tooth 21^a from the Figure 2 position to the Figure 3 position, and, unless the rack 18 were 110 lifted as shown in Figure 3, the tooth 20^a would still be held by the tooth 21^a.

According to the present invention, such lifting of the rack 18 is effected by adjustable means comprising a screw 54 threaded through the portion 18^a of the rack 18, at such a point that, when the rack is in the position shown in Figure 2, the lower end of the screw is in engagement with the roll 51. Upon a single operation of the escapement mechanism, the rack 18 will move 115 from its Figure 2 position to its Figure 4 position. When use is made of a lifting device of fixed range, the rack may be lifted too far or not far enough to clear the pinion, but, by means of the adjusting means of the present invention, the proper 120 adjustment may easily be effected.

To facilitate the movement of the screw 54 over the roll 51, the lower end of the screw is tapered at opposite sides to form 125

- a chisel-point with cam-surfaces 55. These surfaces 55 must always extend across the path of movement of the rack, and, in adjusting the screw, it must be turned in either direction through an angle of 180 degrees or a multiple thereof. The thread of the screw may, however, be made sufficiently fine to enable the adjustment of the screw to a sufficient degree of precision.
- 10 For such adjustment, the screw is provided with a head 56 having a slot 57 to enable the screw to be adjusted by means of a screw-driver and the screw 54 may be locked in adjusted position by means of a locking nut 58.

Variations may be resorted to within the scope of the invention, and portions of the improvements may be used without others.

Having thus described my invention, I

20 claim:

1. In a typewriting machine, a carriage urged in letter-feeding direction, escapement means including a pinion advanced one tooth at each typing operation, a mutilated rack 25 on the carriage normally in mesh with said pinion, a track upon the rack, a roller engaging the track to support the rack, and means for automatically lifting the rack out of engagement with the pinion when the carriage reaches a predetermined position.
2. In a typewriting machine, a carriage urged in letter-feeding direction, escapement mechanism including a bar having a mutilated rack section and a track section, a feeding device to co-operate with the rack section, a roller to support the bar by engaging the track section, and means to free the rack section from said feeding device and adjustable relatively to the roller to vary 35 the extent of such rack movement.
3. In a typewriting machine, a carriage urged in letter-feeding direction, means to control the carriage, including a pinion and a mutilated rack on the carriage meshing 40 with the pinion, means to disengage the carriage-feeding elements, including a roller and a track to run on said roller, and means to automatically disengage the rack from the pinion, including a screw point threaded 45 through the track and adjustable to determine the extent of the rack disengagement.
4. In a typewriting machine, the carriage urged in letter-feeding direction, means to control the carriage, including a pinion and 50 a rack on the carriage meshing with the pinion, and means to disengage the rack from the pinion, including a member threaded through said rack at one side of the teeth thereof for adjustment to vary the extent 55 of the disengaging movement.
5. In a typewriting machine, a carriage urged in letter-feeding direction, means to control the carriage, including a pinion and a rack on the carriage meshing with the 60 pinion, and means to disengage the rack

from the pinion, including a member threaded through said rack at one side of the teeth thereof for adjustment to vary the extent of the disengaging movement, said member having a cam at its effective 70 end to facilitate the action thereof.

6. In a typewriting machine, a carriage urged in letter-feeding direction, means to control the carriage, including a pinion and a rack on the carriage meshing with the 75 pinion, and means to disengage the rack from the pinion, including a member threaded through said rack at one side of the teeth thereof for adjustment to vary the extent of the disengaging movement, said member having oppositely-positioned cams to facilitate its action irrespective of the direction of movement of the carriage.

7. In a typewriting machine, a traveling carriage, and means for automatically tabulating the carriage, comprising a pinion advanced one step at each typing operation, a letter-space rack on the carriage normally meshing with said pinion and having two gaps in its teeth separated by a single tooth, 90 and a device to shift said rack out of engagement with the pinion as the pinion-tooth first engaged by the single tooth of the rack is advanced one step, thereby preventing the single tooth of the rack from being held by 95 the same tooth of the pinion in the second position of the latter, said device being adjustable to vary the extent of such rack-shifting movement.

8. In a typewriting machine, a carriage urged in letter-feeding direction, escapement means including a pinion advanced one tooth at each typing operation and a shiftable rack on the carriage having a row 100 of letter-space teeth normally engaging two teeth of the pinion and a straight portion 105 at one side of said row, and means to disengage the rack temporarily when the carriage reaches a predetermined position, the disengaging means comprising a member 110 over which the straight portion of the rack travels and a device on the rack, adjustable to vary the extent of projection thereof from the rack, to engage said member and ride over the same, thereby disengaging the 115 rack from the pinion for one letter-space movement of the carriage.

9. In a typewriting machine, a carriage urged in a letter-feeding direction, escapement mechanism comprising a pinion rotatable one step at each typing operation and a letter-space rack on the carriage normally in mesh with two teeth of the pinion and having two gaps, separated by a single tooth, for automatically tabulating the carriage to two different columns, and automatic rack-shifting means for releasing the single tooth from the pinion as a result of a single typing operation in the corresponding column, said rack-shifting means in 120 125 130

cluding a member on the rack adjustable to vary the extent of the rack-shifting movement.

10. In a typewriting machine, a carriage urged in a letter-feeding direction, escapement mechanism comprising a pinion rotatable one step at each typing operation and a letter-space rack on the carriage normally in mesh with two teeth of the pinion and having two gaps, separated by a single tooth, for automatically tabulating the carriage to two different columns, and automatic rack-shifting means for releasing the single tooth from the pinion as a result of a single typing operation in the corresponding column, said rack-shifting means including an adjusting screw on the rack to vary the extent of the rack-shifting movement.

11. In a typewriting machine, a carriage urged in a letter-feeding direction, escapement mechanism comprising a pinion rotatable one step at each typing operation and a liftable letter-space rack on the carriage

normally in mesh with two teeth of the pinion and having two gaps, separated by a single tooth, for automatically tabulating the carriage to two different columns, a roll engaging the rack at one side of the rack-teeth to limit the downward movement of the rack, and automatic rack-lifting means for releasing the single tooth from the pinion as a result of a single typing operation in the corresponding column, said rack-lifting means comprising a cam so positioned on the lower side of the rack as to ride over the roll when a typing operation is effected in the column corresponding to the single tooth, and adjustable to vary the extent of the rack-lifting movement.

12. In an automatic tabulating device for a typewriter carriage, an escapement rack having gaps in its teeth separated by a single tooth, and a rack-lifting device comprising a screw movable with the rack to co-operate with a stationary cam for a rack-lifting movement.

HENRY L. PITMAN.
